UNITED STATES PATENT OFFICE.

WILLIAM BELLAIRS, OF MITCHELLVILLE, IOWA.

SNAP-HOOK.

SPECIFICATION forming part of Letters Patent No. 279,477, dated June 12, 1883.

Application filed February 19, 1883. (No model.)

To all whom it may concern:

Be it known that I, WILLIAM BELLAIRS, a citizen of the United States, residing at Mitchellville, in the county of Polk and State of Iowa, have invented certain new and useful Improvements in Snap-Hooks, of which the following is a specification, reference being had therein to the accompanying drawings.

My invention relates to certain new and useful improvements in snap-hooks, but more particularly to improvements on the patent granted to me by the United States Patent Office June 5, 1866, No. 55,229, "snap-hook."

The object of my invention is to construct a snap-hook that can be readily adjusted to the ring in the bridle-bit, neck-yoke, or pole-chain ring, and other like purposes, that is not liable to be detached by accident when in use, that will be durable and efficient, while the cost of construction will be much less than required for the production of the snap covered by my former patent above named.

Referring to the drawings, Figure 1 represents a perspective view of my improved snap, showing the parts in place and the snap closed. Fig. 2 is a longitudinal sectional view, showing the inner and outer hook and spring. Fig. 3 is a detail view, showing the inner hook.

Similar letters refer to similar parts throughout the drawings.

My device, when complete, is formed of an outer and inner hook, a spring and guide-pin, and end loop.

The outer hook, A, is formed with an inwardly-turned lip, a, and outward projections a', with an end loop, C, for the reception of a pole-strap, halter-stem, or other devices whereon snaps are used. Hook A has a longitudinal recess or channel formed on its inner edges, and the outer end has a vertical slot, g, cut entirely through that portion of the hook, as shown in Fig. 2. The inner end of said recess or channel terminates in a square shoulder, h, against which one end of coiled spring f abuts, as shown in Fig. 2.

The inner hook, B, is formed somewhat similar in a part of its construction to the outer hook, A. The outer end of hook B is curved outward and inward to conform to the shape and size of the same part of hook A, and is

provided with inward projections b and b', leaving a sufficient space between said projections for the passage of a ring. An elongated space, e, is provided for the reception and play of the ring, the same as is produced by the construction of the outer hook, A. The inner hook, B, is formed flat, and has an extension rearward, with a vertical projection, D, by which said hook B is retracted when desired to hook or unhook said snap. The under side of said extension is formed with a square shoulder, c, against which the outer end of spring f abuts, and by which said hook B is forced to its place inside of hook, A. An angular slot, d, is formed on or in the lower edge of hook B, its inner end terminating near shoulder c, through which passes stop-pin i, as shown in Fig. 2.

A coiled spring, f, is placed in a recess formed in the shank of hook A, the inner end of which rests against the shoulder h, and the outer end against the shoulder c, as shown in Fig. 2.

In putting the parts together, the inner hook, B, is inserted by its inner end through slot g to near the place for the pivot-pin or stop-pin i, when spring f is placed in the recess formed in hook A. Then the hook B is pushed in until the stop-pin i can be pushed through slot d, when the parts are secured in place.

The operation is as follows: When desired to hook the snap onto a ring, the thumb or finger of the operator is pressed against the projection D, when the inner hook is retracted, leaving an open space between the points a and a'. As soon as the ring has passed into the space e the projection D is released, when the inner hook, B, is thrown out to its place against the stop-pin i by the coiled spring f.

Having thus described my invention, what I claim, and desire to secure by Letters Patent, is—

1. A snap-hook composed of an outer and inner hook, the inner hook sliding within the outer hook, as described, the outer hook having an end loop for the reception of a strap or rope, said hook slotted through its outer end, and recessed as described, the inner hook slotted and formed as described, and adapted to work against a coiled spring located in the shank

of the outer hook, substantially as and for the purpose set forth.

2. The combination of the outer hook, A, having an end loop, C, slot *g*, shoulder *h*, pin *i*, and points *a* and *a'*, with hook B, having points *b* *b'*, projection D, slot *d*, and shoulder *c*, adapted to work against spring *f* and pin *i*, substantially as shown and specified.

In testimony whereof I affix my signature in presence of two witnesses.

WILLIAM BELLAIRS.
